UNITED STATES PATENT OFFICE.

JACOB AVIDAN, OF FREEPORT, NEW YORK, ASSIGNOR TO LIPPMANN, SPIER & HAHN,
OF NEW YORK, N. Y.

DESIGN FOR A VANITY CASE.

Application filed February 7, 1925. Serial No. 12,308. Term of patent 7 years.

To all whom it may concern:

Be it known that I, JACOB AVIDAN, a citizen of the United States, residing at Freeport, in the county of Nassau and State of New York, have invented a new, original, and ornamental Design for Vanity Cases, of which the following is a specification, reference being had to the accompanying drawing, forming part thereof.

The figure is a perspective of a vanity case, showing my new design.

I claim:

The ornamental design for a vanity case, as shown.

JACOB AVIDAN.
